UNITED STATES PATENT OFFICE.

ALVIN DINGS, OF MILWAUKEE, WISCONSIN, ASSIGNOR TO DINGS-ELECTRO MAGNETIC SEPARATOR CO., OF MILWAUKEE, WISCONSIN, A CORPORATION OF WISCONSIN.

MAGNETIC SEPARATOR.

986,554.

Specification of Letters Patent. Patented Mar. 14, 1911.

Application filed March 6, 1907. Serial No. 360,820.

To all whom it may concern:

Be it known that I, ALVIN DINGS, a citizen of the United States, residing at Milwaukee, county of Milwaukee, and State of Wisconsin, have invented new and useful Improvements in Magnetic Separators, of which the following is a specification.

My invention relates to improvements in electromagnetic separators of that class in which the material is conveyed through a magnetic zone by a non-magnetic conveyer and the magnetite removed from the conveyer by the direct attraction of moving auxiliary pole pieces.

15 The object of this invention is to provide a uniform magnetic zone, and regulate the intensity thereof, also to provide plural zones of different intensity.

20 A further object is to provide means for supporting and energizing the auxiliary pole pieces.

In the following description reference is had to the accompanying drawings, in which,

25 Figure 1 is a side elevation of a magnetic separator embodying my invention. Fig. 2 is a plan view of the same. Fig. 3 is a detail view showing a modified form of auxiliary pole piece comprising a continuous 30 ring. Fig. 4 is a vertical central sectional view drawn longitudinally of the conveyer belt. Fig. 5 is a sectional view of one of the magnets drawn through its axis and that of the adjusting screw. Fig. 6 is a diagrammatic view of a modified form of construction.

Like parts are identified by the same reference characters throughout the several views.

The electromagnet coils 1 are four in number and are grouped in pairs with the members of each pair on opposite sides of the horizontally disposed belt 2, which belt serves as a conveyer for the material. The coils composing a pair are wound in the 40 same direction and connected at the top by a pole piece 3 which is provided with core posts 4 which extend downwardly through the magnet coils and rest upon a bed 5. Lower pole pieces 6 are movably mounted 45 upon the posts 4 and are adjusted by means of adjusting screw rods 7 which have swiv- 50 eled connection with the upper pole piece 3 between the coils, the screw rods 7 having a collar 9 bearing against the under surface

of the pole piece 3 and a head 10 bearing upon the upper surface of such pole piece. The rod has screw threaded engagement with the lower pole piece 6 so that by turning the rod this pole piece may be raised or lowered. The conveyer belt 2 extends horizontally between the pole pieces and with one of the adjusting screws 7 on each side of the belt between such belt and the electromagnet coil 1. The upper pole piece is provided between the magnet coils with a downwardly extending segmental member 12, having a segmental channel 13 therein and the lower pole piece is provided with an upwardly extending member 14, the latter being in close proximity to the belt when this pole piece is 60 raised as shown in the drawings. The other pair of electromagnet coils is provided with similar pole pieces faced in the opposite direction, i. e., the segmental members 12 and 14 of the respective upper and lower 65 pole pieces are faced toward each other and a cap piece 16 of non-magnetic material resting upon the pole pieces 3 is provided with a bearing 17 for the shaft 18 which extends downwardly through the bearing and is provided at its lower end with a wheel shaped carrier 19 to which an annular series of auxiliary pole pieces 20 are secured in a position to pass successively through segmental channels 13 of both of the pole pieces 3 when the 70 carrier is rotated. The auxiliary pole pieces are formed of magnetizable material and are secured to the non-magnetic carrier by any suitable means, such as bolts 23. At their 75 lower ends the auxiliary pole pieces have 80 converging outer and inner surfaces 24, whereby the lower ends of the pole pieces assume the form of a blunt wedge having a curved edge corresponding with the curvature of the channels 13 of the pole pieces and 85 the line of rotation of the auxiliary pole pieces. The object of thus tapering the lower ends of these pole pieces is to concentrate the magnetic lines of force in a narrow but intense magnetic field. The object 90 of providing the segmental channel 13 is to increase the area of magnetic flux to the auxiliary pole pieces, which are thus made to pass in close proximity to a plurality of 95 magnetic surfaces.

100 In operation the shaft 18 with the carrier 19 and the auxiliary pole pieces are rotated from any suitable source of power and the

conveyer belt 2 is caused to travel longitudinally, thus conveying the material thereon across the magnetic field of the first set of magnets and then across the magnetic field of the second set, thus exposing the magnetite to the attraction of the auxiliary pole pieces at two points. It will be understood that the magnetite will be lifted from the conveyer by the attraction of the pole pieces 20 and will be discharged from such pole pieces in the neutral zone when passing from one set of magnets to the next. By means of the screw rods 7, the intensity of the magnetic field may not only be varied by raising and lowering the pole pieces 6 but it is also possible to have magnetic fields of different intensity by adjusting the pole pieces 6 of one set of magnets at a lower level or at a greater distance from the conveyer 2 than the pole piece 6 of the other set of magnets.

In order that the adjustment may be transversely uniform or equal for both magnets of a set the screw rods 7 are provided near their upper ends with sprocket wheels 27 around which a sprocket chain 28 extends and connects the rods on opposite sides of the conveyer 2. One of the rods is provided with a hand wheel 29 by turning which both rods of the set will be simultaneously actuated and the lower pole piece 6 uniformly adjusted at both ends.

In Fig. 3 I have illustrated an auxiliary pole piece comprising a continuous ring 30 which is substituted for the series of pole pieces 20, shown in the other views. The ring is mounted upon the carrier 19 in the same manner as the pole pieces 20. If the ring is used a brush 31 is preferably employed in the neutral zone to remove the magnetite which would otherwise adhere through residual magnetism. The magnets of the second set are however preferably wound in the opposite direction from those of the first set, whereby the corresponding pole pieces of the sets will be of opposite polarity.

In Fig. 6 I have illustrated the form of construction in which a carrier 40 of non-magnetic material is employed to convey the magnetite from the belt. In this case the carrier comprises a plane disk without auxiliary pole pieces, the disk being arranged to extend between the upper pole piece and the belt, whereby the magnetite will be drawn by the direct attraction of the upper polar projection 12 against the under surface of the carrier and retained in such position until it passes out of the magnetic field when it will be permitted to drop at the side of the belt.

Having thus described my invention what I claim as new and desire to secure by Letters Patent is,

1. The combination of a plurality of pairs 65 of separated upright electromagnetic coils, a

non-magnetic conveyer extending between the coils of each pair in a horizontal plane, pole pieces connecting said coils above and below the conveyer and extending inwardly from the coils with extremities extending in the direction of the conveyer at the inner sides of the coil, the upper pole piece extremity being provided with segmental channels in arcs described from an axis located centrally between them, a shaft located 75 on said axis and provided with a rotary carrier and a series of auxiliary pole pieces mounted upon said carrier in a position to revolve successively through said segmental channels above the upper surface of the conveyer and to points laterally distant therefrom on each side of the conveyer.

2. The combination with a shaft, a rotatable carrier wheel connected with the shaft, an annular series of magnetizable members 85 mounted upon said wheel and adapted to serve as auxiliary pole pieces, a conveyer of less width than the diameter of the wheel extending across one face of the wheel, and sets of electromagnets straddling said conveyer and provided with polar projections extending inwardly and toward the conveyer and all that portion of the wheel which is in registry with the conveyer.

3. The combination of a conveyer, a carrier arranged to revolve in a plane parallel to the surface of the conveyer and across the upper face thereof, a series of auxiliary pole pieces mounted upon said carrier, electromagnetic coils at the sides of the conveyer 100 arranged in pairs on opposite sides of the carrier, pole pieces connecting the coils of each pair with each other and provided with polar projections extending in the direction of the conveyer above and below the conveyer and carrier, the polar projections on the side of the conveyer occupied by the carrier being provided with segmental channels adapted to receive the upper ends of said polar projections successively when the 110 carrier is actuated.

4. The combination of a conveyer, a carrier arranged to revolve in a plane parallel to the surface of the conveyer and across the upper face thereof, a series of auxiliary 115 pole pieces mounted upon said carrier, electromagnetic coils at the sides of the conveyer arranged in pairs on opposite sides of the carrier, pole pieces connecting the coils of each pair with each other and provided with polar projections extending in the direction of the conveyer above and below the conveyer and carrier, the polar projections on the side of the conveyer occupied by the carrier being provided with segmental channels adapted to receive the upper ends of said polar projections successively when the 125 carrier is actuated, the lower margins of said polar projections being wedge shaped and arranged to travel across the face of the 130

conveyer with the edges of the wedge shaped portions transverse to the conveyer and in close proximity thereto.

5. The combination of a conveyer, a carrier arranged to revolve in a plane parallel to the surface of the conveyer and across the upper face thereof, a series of auxiliary pole pieces mounted upon said carrier, electro-magnetic coils at the sides of the conveyer arranged in pairs on opposite sides of the carrier, pole pieces connecting the coils of each pair with each other and provided with polar projections extending in the direction of the conveyer above and below the conveyer and carrier, together with a set of adjusting screws connecting the respective ends of the pole pieces for each pair of coils and arranged to actuate one of said pole pieces relatively to the other, said screws having motion transferring connections with each other, whereby both will be actuated simultaneously for the transmission of equal motion to both ends of the pole piece.

6. The combination of a conveyer, a car-

rier arranged to revolve in a plane parallel 25 to the surface of the conveyer and across the upper face thereof, a series of auxiliary pole pieces mounted upon said carrier, electro-magnetic coils at the sides of the conveyer arranged in pairs on opposite sides of the 30 carrier, pole pieces connecting the coils of each pair with each other and provided with polar projections extending in the direction of the conveyer above and below the conveyer and carrier, the coils of the second set 35 being oppositely wound from those of the first set and the pole pieces on the respective sets being relatively independently adjustable to increase or diminish the effect upon the magnetic material carried by the 40 conveyer.

In testimony whereof I affix my signature in the presence of two witnesses.

ALVIN DINGS.
